UNITED STATES PATENT OFFICE.

CHARLES R. DENNY, OF WASHINGTON, DISTRICT OF COLUMBIA.

DESIGN FOR A TELEPHONE ATTACHMENT.

48,105.

Specification for Design.

Patented Nov. 9, 1915.

Application filed September 14, 1915. Serial No. 50,714. Term of patent 3½ years.

To all whom it may concern:

Be it known that I, CHARLES R. DENNY, a citizen of the United States, residing at Washington, in the District of Columbia, have invented a new, original, and ornamental Design for Telephone Attachments, of which the following is a specification, reference being had to the accompanying drawing, forming a part thereof.

2 is an end view of a telephone attachment, showing my new design.

I claim:

The ornamental design for a telephone attachment, as shown.

CHARLES R. DENNY.

Witnesses:

BENNETT S. JONES,

ESTHER H. JOHNSON.
